US00D880357S

(12) **United States Design Patent** (10) Patent No.: **US D880,357 S**
(45) Date of Patent: ** *Apr. 7, 2020

(54) **ALLTERRAIN VEHICLES**

(71) Applicant: **ENSENOR ENTERPRISES LIMITED**, Nicosia (CY)

(72) Inventor: **Sergei Samokhvalov**, Kyiv (UA)

(73) Assignee: **ENSENOR ENTERPRISES LIMITED**, Nicosia (CY)

(*) Notice: This patent is subject to a terminal disclaimer.

(**) Term: **15 Years**

(21) Appl. No.: **35/502,325**

(22) Filed: **Dec. 9, 2016**

(80) **Hague Agreement Data**

Int. Filing Date: **Dec. 9, 2016**

Int. Reg. No.: **DM/094168**

Int. Reg. Date: **Dec. 9, 2016**

Int. Reg. Pub. Date: **Jan. 20, 2017**

(30) **Foreign Application Priority Data**

Oct. 21, 2016 (UA) 201601737

(51) LOC (12) Cl. **12-13**

(52) U.S. Cl.

USPC **D12/1**

(58) **Field of Classification Search**

USPC D12/1-3

CPC B60F 3/0069; B60F 3/0061; B63H 21/175
